UNITED STATES PATENT OFFICE

2,093,051

MANUFACTURE OF CIGARETTES

Rowland Frank May, Middlesex, England, assignor to Filter Tips Limited, London, England, a British company

Application October 25, 1934, Serial No. 750,010
In Great Britain November 2, 1933

16 Claims. (Cl. 131—39)

This invention relates to the manufacture of cigarettes and is particularly concerned with the manufacture on the continuous rod principle of cigarettes containing filter tips, wads, stubs, tufts, tubes or other insertions enabling economy in tobacco to be obtained, and the invention includes the manufacture of cigarettes of this kind wherein the insertion consists of tobacco of different quality or character to that of which the major part of the cigarette is constituted, the insertion being located at the mouthpiece end of the cigarette or at an intermediate position in the length of the cigarette.

The invention has for its object to enable cigarettes such as referred to above to be produced in a simple and efficient manner on the continuous rod principle and furthermore to provide simple apparatus for this purpose which is capable of being readily applied to existing continuous rod cigarette-making machinery.

According to the present invention, in the manufacture on the continuous rod principle of cigarettes containing a filter tip or other insertion, the insertions are first applied to the continuous paper strip and are affixed thereto as by means of adhesive, and the continuous tobacco filling fed from the tobacco feed hopper is cut into lengths which are delivered or transferred on to the paper strip between the insertions, the paper strip being then wrapped around the composite filling to produce a continuous cigarette rod which is cut off into lengths to obtain cigarettes each containing a filling of tobacco and a filter tip or other insertion.

In one embodiment the lengths of tobacco filling as they are cut off are applied directly on to the paper strip between the insertions thereon.

In a further embodiment the tobacco filling and the paper strip are fed intermittently and the lengths cut off from the tobacco filling are transferred by an intermittently movable transfer drum or like carrier and deposited therefrom on the paper strip between the insertions thereon.

According to the invention, moreover, apparatus for the production on the continuous rod principle of cigarettes provided with filter tips or other insertions comprises mechanism including means for applying insertions at spaced positions to the paper strip and means for feeding the continuous tobacco filling to a cut-off device by which the tobacco filling is cut into lengths, such mechanism being arranged or adapted so that the lengths of tobacco cut off from the continuous tobacco filling are delivered or transferred on to the paper strip in positions between the insertions on the said strip.

In one embodiment the apparatus may comprise means for feeding the continuous tobacco filling from the tobacco feed hopper to a position

at which it is directed on to the continuous paper strip to which the insertions have been applied at spaced positions, and means for cutting the continuous tobacco filling into lengths, such cutting means being arranged so that the lengths as they are cut off are delivered into the spaces between the insertions. Means may be provided for obturating the feed movement of the tobacco filling momentarily after each cutting operation so that the leading end of the continuous filling is delivered on to the paper strip behind the respective insertion thereon. Furthermore, means may be provided whereby the trailing end of each length cut off from the tobacco filling is positively deposited on the paper strip. Such means may comprise a member adapted to engage above the tobacco and actuated in such manner as to engage the tobacco immediately after the cutting operation and place the same upon the paper strip, and such member may be adapted and operated to guide the leading end of the continuous tobacco filling behind the respective insertion.

Preferably the paper strip is led around a roller at a position immediately beneath the cut-off point of the tobacco filling so that the insertions in travelling around an arcuate path up to and below the said cut-off point close up behind the end of the cut-off length of tobacco filling deposited on the paper strip.

According to a further embodiment wherein the continuous tobacco filling and the paper strip are fed intermittently, the apparatus comprises a transfer drum or like intermittently movable carrier arranged to receive the leading part of the tobacco filling and, after such part is cut off, to carry the same into a position parallel with the paper strip, and means for ejecting the length of tobacco from the carrier on to the paper strip between the insertions thereon. The intermittently movable carrier comprises a drum having a sleeve-like extension slotted from one end to provide a number of open chambers into which the tobacco filling is fed axially and from which the lengths of tobacco filling are ejected laterally. The ejection of the lengths of tobacco filling from the carrier is effected by means of a bar or like element extending within the sleeve-like extension of the drum and operated so as to eject the lengths of tobacco filling bodily from the open chambers and to deposit such lengths on the paper strip between the insertions thereon.

Fixed inner and outer walls or guide members are arranged to co-operate with the inner and outer peripheries of the sleeve-like part of the drum so as to prevent displacement of the lengths of tobacco from the chambers during passage from the point of inlet to the point of discharge.

The tobacco filling carried from the tobacco

feed hopper on an endless belt is fed to the cut-off device by means of pressure rollers.

The filter tips or insertions may be applied to the paper strip by mechanism comprising a wheel or disc having circumferentially extending grooves into which the insertions are applied and a pasting device associated with the wheel or disc and arranged to apply adhesive to the insertions prior to the application of the continuous paper strip thereto.

Generally it will be advisable or essential except where the insertions consist of wads or tufts of material of the nature of cottonwool, to enclose the insertion material in a paper tube, sleeve or wrapper before its application to the paper strip. By such means filter tips or wads made from strip material such as crepe paper, with or without intervening layers of filtering material and rolled, bunched, folded or otherwise formed to a circular cross-section, may be retained in formation while the lengths of tobacco are placed between the insertions and the paper strip wrapped around the composite filling produced. Similarly, if the insertion material consists of tobacco, the provision of an enclosing tube of wrapping therefor enables the insertions to be previously prepared, for instance, on a continuous rod machine and facilitates the placing and retention of the tobacco insertions on the paper strip.

The invention is hereinafter described by way of example with reference to the accompanying diagrammatic drawings, in which:—

Figure 1 is a perspective view illustrating one embodiment of the invention;

Figures 2 and 3 are fragmentary views of part of Figure 1 illustrating the manner in which the lengths of tobacco filling are deposited on the paper strip;

Figure 4 is a part sectional side elevation illustrating a modification;

Figure 5 is a section on the line 5—5, Figure 4; and

Figure 6 is a side elevation illustrating means for applying the filter tips or insertions to the paper strip.

In carrying the invention into effect according to one embodiment and with reference to Figures 1, 2, 3, and 6 of the accompanying diagrammatic drawings, the continuous tobacco filling 1 carried from the tobacco feed hopper 2 on an endless belt 3 passes into a collector tube 4 by which the filling 1 is guided in relation to a cut-off device 5 which may be a rotary disc or bladed cutter. In Fig. 1 there is shown a cutter disc 5 mounted on shaft 5b. The disc carries a blade 5a which intermittently engages the tobacco rod to sever a length therefrom. In order to ensure proper feed movement of the filling 1 through the collector tube 4, the latter may be interrupted for the accommodation of a pair of grooved pressure rollers 6 driven through suitable mechanism (not shown) and whereby the filling 1 is drawn through the tube 4 and fed through the terminal extension 4a thereof. The continuous paper strip 7 to which filter tips or insertions 8 have been previously applied is led around a roller 9 disposed immediately beneath the cut-off point of the tobacco filling and thence passes to the tube-forming device 10. As the continuous tobacco filling 1 issues from the tube 4a it is delivered, as shown in Figures 1 and 3, onto the paper strip 7 so that its leading end is behind the respective insertion 8. The cutter 5 is timed and arranged so as to sever the desired

length from the filling 1 and preferably also is disposed so that the cutting action is in a downward direction or in a direction which is mainly downward so that the action of the cutter assists the placing of the trailing end of the cut-off 5 length of tobacco filling on to the paper strip 7. In order to ensure the correct deposition of the trailing end of the cut-off length of the tobacco filling 1, however, a member 11 may be provided which is mounted and actuated so that immediately after the cutting operation it engages above the trailing part of the cut-off length of tobacco filling and positively deposits the same on the paper strip and so that it thereafter moves in the direction of the paper strip but initially 10 at a reduced speed so that by obturating the flow of the tobacco filling 1 it ensures the deposition of the leading end of the filling behind the respective insertion 8, as shown in Figure 4. In Fig. 1, there is shown a mechanism for actuating member 11. As shown, member 11 is carried on bar 11a provided at the opposite end with a slot 11c cooperating with a fixed pin 11e. The bar 11a, carrying the member 11, is provided with a rectangular slot 11b, in which is positioned a cam 11d rotated by a shaft 11f. This construction, which effects the desired movement of member 11, is conventional and not considered to be novel per se. If desired the feed mechanism of the tobacco filling may be arranged or caused to 25 slow down, or even may be interrupted, during the cutting operation. Furthermore, the tobacco filling may be fed at a mean speed which is slower than the mean speed of the paper strip, the member 11 serving, as shown in Figure 2, to ensure 30 the eventual placing of the leading end of the filling behind the respective insertion 8. By arranging the roller 9 with its axis immediately beneath and slightly in front of the cut-off point the insertions 8 move along an arcuate path at 35 this position and as they pass from the arcuate path to a straight path move up to the rear end of the cut-off length of tobacco filling deposited on the paper strip 7. Such an arrangement facilitates the deposition of the rear end of the 40 cut-off length of tobacco in front of the respective insertion 8. After the placing of the lengths of tobacco between the insertions as described, the composite filling produced is wrapped in the 45 continuous paper strip in known manner and the continuous rod produced subsequently is subdivided to produce cigarettes each containing a 50 length of tobacco and an insertion, the insertion being located at the mouthpiece end or at an intermediate position as desired.

The insertions 8 may be applied to the paper strip 7 in any convenient manner. For example, as illustrated in Figure 6 the insertions, consisting of filter tips or wads or lengths of tobacco enclosed in tubes, sleeves or wrappers, may be ejected from chambers 12a in an intermittently rotatable drum 12 by means of a plunger 13 and be directed through a guide tube 14 into a circumferentially extending groove 15a in a wheel or disc 15 so that the insertion 8 is positioned 55 against an abutment 15b. Drum 12 may be intermittently rotated in the same manner as cylinder 11 of U. S. Patent No. 1,967,610 or in the same manner as the rotary carrier 1 of British Patent No. 416,128. The insertions 8 are fed to 60 the chambers 12a from any suitable construction of forming unit 16 by means of a plunger 16a. The insertions 8 disposed in the groove 15a extend slightly beyond the periphery of the wheel or disc 15 for the application of adhesive as by 65 70 75 75

means of a disc 17 co-operating with a pasting device 18. The paper strip 7 is led around a roller 19 so as to engage the periphery of the wheel or disc 15 and thus, as the latter rotates, the 5 insertions 8, to which adhesive has been applied by the disc 17, are carried into engagement with the paper strip 7 and are conveyed away thereby from the wheel or disc 15. Preferably the adhesive is applied only to the leading end portion 10 of the insertions 8 to facilitate the passage of the insertions around the roller 9.

In the case of stubs or tufts of material in the nature of cottonwool, these may be applied to the paper strip in any desired manner and 15 fixed thereon by adhesive or by other suitable means.

According to a modification, as illustrated in Figures 4 and 5, the paper strip 7 is guided over a roller 9 so as to extend parallel with and substantially below the tube 4 through which the 20 tobacco filling 1 is fed, and a drum 20 is provided, such drum having a sleeve-like extension 20a formed with slots 20b extending from one end so as to provide open chambers which in 25 one position are in alignment with the outlet from the tube extension 4a and in the other position are disposed immediately above the paper strip 7 carried on a guide 21. Drum 20 may be intermittently rotated in the same manner as 30 cylinder 11 of U. S. Patent No. 1,967,610 or in the same manner as the rotary carrier 1 of British Patent No. 416,128. In this arrangement the continuous tobacco filling and the paper strip are fed intermittently. Thus, when the tobacco 35 filling 1 has passed into the respective chamber 20b to the full or desired extent, the feed is arrested and the cutter 5 is actuated to sever the length of tobacco filling and the drum 20 is moved so as to bring a fresh chamber into alignment with the tube extension 4a. Simultaneously with the cutting action a length of tobacco 40 is ejected from the lowermost chamber 20b by means of a bar 22 carried and operated by an arm 23 which may be actuated by cam mechanism through a rod 24, the bar 23 preferably having a concave under face so as to position the length of tobacco filling accurately on the paper strip 7 between the insertions 8. Alternatively the feed movement of the paper strip may take 45 place while the tobacco feeding mechanism is stationary, in which case the ejection of the length of tobacco from the drum on to the paper strip will take place while the tobacco filling is passing into the respective chamber.

In order to prevent displacement of the lengths 50 of tobacco filling from the chambers in passing from the point of inlet to the point of discharge, fixed inner and outer members 25, 26 respectively are provided to co-operate with the inner and 55 outer peripheries of the sleeve-like part 20a, as shown in Figure 6.

It will be understood that the invention is not limited to the particular embodiments hereinbefore described. For example, the means for 60 diverting or transferring the tobacco from the belt in cut lengths on to the paper strip may be otherwise constructed and arranged and the cut-off device may be modified in various ways. Furthermore, it will be understood that where the 65 filter tip or other insertion is, by its method of formation or inherent character, adapted to retain its formation, the enclosing wrapper therefor may be dispensed with and the insertion may be fixed directly to the paper strip. Furthermore, any other suitable means may be provided 70

for applying the filter tips or insertions to the paper strip.

I claim:

1. A method of manufacturing, on the continuous rod principle, cigarettes containing a filter tip or other insertion, comprising supplying a continuous paper strip, affixing the insertions to said strip at spaced intervals, supplying a continuous preformed tobacco rod, cutting said tobacco rod into successive and equal lengths, each length being equal to the distance 10 between the insertions affixed to the paper strip, positioning said lengths of tobacco rod on said strip between the affixed insertions, and wrapping the strip around the lengths of tobacco rod 15 and insertions to form a continuous rod consisting of alternate lengths of tobacco and insertions.

2. A method of manufacturing, on the continuous rod principle, cigarettes containing a filter tip or other insertion, comprising supplying a continuous paper strip, affixing the insertions to said strip at spaced intervals, supplying a continuous preformed tobacco rod, cutting said tobacco rod into successive and equal lengths, 20 each length being equal to the distance between the insertions affixed to the paper strip, positioning said lengths of tobacco rod on said strip between the affixed insertions, wrapping the strip around the lengths of tobacco rod and insertions to form a continuous rod consisting of alternate 25 lengths of tobacco and insertions, and cutting the continuous rod into lengths each containing a tobacco filling and an insertion.

3. A method of manufacturing, on the continuous rod principle, cigarettes containing a filter tip or other insertion, comprising supplying a continuous paper strip, affixing the insertions to said strip at spaced intervals, running a continuous preformed tobacco rod onto said strip between the insertions, cutting off successive and equal lengths of said tobacco rod as it is deposited on the strip to fill the spaces between the insertions, and wrapping the strip around the tobacco lengths and insertions to form a continuous rod 30 consisting of alternate lengths of tobacco and insertions.

4. A method of manufacturing, on the continuous rod principle, cigarettes containing a filter tip or other insertion, comprising supplying a continuous paper strip, affixing the insertions to said strip at spaced intervals, running a continuous preformed tobacco rod onto said strip between the insertions, cutting off successive and equal lengths of said tobacco rod as it is deposited 40 on the strip to fill the spaces between the insertions, wrapping the strip around the tobacco lengths and insertions to form a continuous rod 45 consisting of alternate lengths of tobacco and insertions, and cutting the continuous rod into lengths each containing a tobacco filling and an insertion.

5. A method according to claim 1, wherein the lengths of tobacco rod, as they are cut off from the continuous preformed tobacco rod, are applied directly onto the paper strip between the insertions thereon.

6. A method of manufacturing, on the continuous rod principle, cigarettes containing a filter tip or other insertion, comprising supplying a continuous paper strip, affixing the insertions to said strip at spaced intervals, supplying a continuous tobacco rod, cutting said tobacco rod into successive lengths equal to the distance 70 between the insertions affixed to the paper strip,

intermittently transferring the lengths cut off the tobacco rod from a position of alignment with the tobacco rod to a position over said strip, depositing the transferred length of tobacco onto the strip between said insertions, and wrapping the strip around the tobacco lengths and insertions to form a continuous rod consisting of alternate lengths of tobacco and insertions.

5 7. An apparatus for the production, on the continuous rod principle, of cigarettes provided with filter tips or other insertions, comprising means for supplying a continuous paper strip, means for affixing insertions to said strip at spaced intervals, means for supplying a continuous tobacco rod, and means for cutting successive lengths from said tobacco rod for delivery onto said strip between the spaced insertions.

10 8. An apparatus for the production, on the continuous rod principle, of cigarettes provided with filter tips or other insertions, comprising means for supplying a continuous paper strip, means for affixing insertions to said strip at spaced intervals, means for supplying a continuous tobacco rod onto said strip, and cutting 15 means operable intermittently for severing lengths from the tobacco rod for deposition between the spaced insertions.

15 9. An apparatus for the production, on the continuous rod principle, of cigarettes provided with filter tips or other insertions, comprising means for supplying a continuous paper strip, means for affixing insertions to said strip at spaced intervals, means for supplying a continuous tobacco rod onto said strip, cutting means operable 20 intermittently for severing lengths from the tobacco rod for deposition between the spaced insertions, and means for timing the feed of the tobacco rod so that after each cutting operation the leading end of the continuous tobacco rod 25 is delivered onto the paper strip behind an insertion.

30 10. An apparatus for the production, on the continuous rod principle, of cigarettes provided with filter tips or other insertions, comprising means for supplying a continuous paper strip, means for affixing insertions to said strip at spaced intervals, means for supplying a continuous tobacco rod onto said strip, cutting means operable 35 intermittently for severing lengths from the tobacco rod for deposition between the spaced insertions, and means for moving the trailing end of each length of tobacco into position on 40 said paper strip in front of an insertion.

35 11. An apparatus for the production, on the continuous rod principle, of cigarettes provided with filter tips or other insertions, comprising means for supplying a continuous paper strip, means for affixing insertions to said strip at spaced intervals, means for supplying a continuous 45 tobacco rod onto said strip, cutting means operable intermittently for severing lengths from the tobacco rod for deposition between the spaced insertions, and means for timing the feed of the tobacco rod so that after each cutting operation 50 the leading end of the continuous tobacco rod is delivered onto the paper strip behind an insertion, and means for moving the trailing end of each length of tobacco into position on said paper strip in front of an insertion.

55 12. An apparatus for the production, on the continuous rod principle, of cigarettes provided with filter tips or other insertions, comprising means for supplying a continuous paper strip, means for affixing insertions to said strip at 60 spaced intervals, means for supplying a continu-

ous tobacco rod onto said strip, cutting means operable intermittently for severing lengths from the tobacco rod for deposition between the spaced insertions, and means for moving the trailing end of each length of tobacco into position on said paper strip in front of an insertion and for guiding the leading end of the next succeeding length to a position on the paper strip behind said insertion.

65 13. An apparatus for the production, on the continuous rod principle, of cigarettes provided with filter tips or other insertions, comprising means for supplying a continuous paper strip, means for affixing insertions to said strip at spaced intervals, means for supplying a continuous tobacco rod, means for cutting successive lengths from said tobacco rod, an intermittently operated carrier having chambers for receiving said cut-off lengths of tobacco and moving the same to a position over said paper strip, and 70 means for ejecting said lengths of tobacco onto said strip between said insertions.

75 14. An apparatus for the production, on the continuous rod principle, of cigarettes provided with filter tips or other insertions, comprising means for supplying a continuous paper strip, means for affixing insertions to said strip at spaced intervals, means for supplying a continuous tobacco rod, means for cutting successive lengths from said tobacco rod, an intermittently 80 movable carrier drum having a tubular extension provided with a plurality of longitudinally extending slots to provide a plurality of circumferentially spaced chambers for receiving said cut-off lengths of tobacco, and means for ejecting said lengths of tobacco from said chambers when in a position over said paper strip.

85 15. An apparatus for the production, on the continuous rod principle, of cigarettes provided with filter tips or other insertions, comprising means for supplying a continuous paper strip, means for affixing insertions to said strip at spaced intervals, means for supplying a continuous tobacco rod, means for cutting successive lengths from said tobacco rod, an intermittently 90 movable carrier drum having a tubular extension provided with a plurality of longitudinally extending slots to provide a plurality of circumferentially spaced chambers for receiving said cut-off lengths of tobacco, a bar mounted within said tubular extension of the drum, and means for moving said bar radially of the drum to eject a length of tobacco from one of said chambers.

95 16. An apparatus for the production, on the continuous rod principle, of cigarettes provided with filter tips or other insertions, comprising means for supplying a continuous paper strip, means for affixing insertions to said strip at spaced intervals, means for supplying a continuous 100 tobacco rod, means for cutting successive lengths from said tobacco rod, an intermittently movable carrier drum having a tubular extension provided with a plurality of longitudinally extending slots to provide a plurality of circumferentially spaced chambers for receiving said cut-off lengths of tobacco, means for ejecting said lengths of tobacco from said chambers when in a position over said paper strip, and means co-operating with the inner and outer peripheries of said tubular extension for guiding a length of tobacco into said chambers and retaining the same in said chambers while the drum moves from the point of feed to the point of discharge.
